UNITED STATES PATENT OFFICE.

LOUIS F. EISELE, OF PHILADELPHIA, PENNSYLVANIA.

SHOWER-BATH STALL.

1,318,329.

Specification of Letters Patent.

Patented Oct. 7, 1919.

Application filed July 9, 1917. Serial No. 179,303.

To all whom it may concern:

Be it known that I, LOUIS F. EISELE, a citizen of the United States, residing at Philadelphia, in the county of Philadelphia and State of Pennsylvania, have invented 5 certain new and useful Improvements in Shower-Bath Stalls, of which the following is a specification.

My invention relates to shower bath stall 10 construction and more particularly consists of an improved construction of door and door housing for shower bath stalls.

Prior to my invention it was extremely difficult and expensive to construct high 15 grade shower bath stalls including plate glass mirror doors and marble casings, since the doors are heavy and require strong mountings and housings. The result was that bulky and unsightly fixtures were used 20 in order to insure the desirable durability and to prevent the sagging and breaking of the glass doors and mountings. In addition to this, the installation was slow, tedious and expensive.

One object of my invention is to construct 25 a shower bath stall including a heavy door having a glass mirror mounted in such manner that it will be durable and neat in appearance.

Another object is to so arrange the parts 30 of my invention that a shower bath stall of the above described type can be easily and quickly manufactured at a low cost.

These objects, and other advantageous 35 ends which will be described hereinafter, I attain in the following manner, reference being had to the accompanying drawings in which:

Figure 1 is a front elevation of sufficient 40 of a shower bath stall to illustrate my invention.

Fig. 2 is an enlarged section on the line 4-2 of Fig. 1, the same being broken away within its length.

Fig. 3 is an enlarged section on the line 3-3 of Fig. 1.

Fig. 4 is a fragmentary section on the line 4-4 of Fig. 3.

Fig. 5 is an enlarged fragmentary view of 0 the upper end of Fig. 2.

Fig. 6 is a fragmentary section showing a slight modification in the frame for the door mirror.

Referring to Figs. 1 to 5 inclusive of the 5 drawings, 1 represents a shower bath stall casing which is preferably made of stone or

marble slabs and has an opening 2 which can be closed by a door 3.

The door 3 includes a plate glass panel 4 which is preferably made in the form of a 60 mirror and is mounted within a frame 5. This frame forms one of the important features of my invention since its construction provides an extremely durable door as will hereinafter be more clearly set forth. 65

The frame 5 consists of two side channels 6 and 7 and a bottom channel 8. These channels are preferably made of nickel plated brass and are of substantially U- 70 shape cross section as clearly shown in Figs. 2 and 3. Filling strips 9 and 10 are positioned within the channels 6 and 7 and are preferably soldered to the inner walls thereof. These filling strips serve as reinforcing 75 members for the sides of the channels and their outer edges also serve as abutting means for the oppositely disposed side edges of the glass panel 4 (see Fig. 3). The bottom channel 8 also has a filling strip 11 positioned within its side portions in a manner 80 similar to the positioning of the filling strips 9 and 10, and this filling strip 11 serves as a reinforcement for the sides of the bottom channel 8 and also serves as a rest for the bottom edge of the panel 4. 85

The side channels 6 and 7 and the bottom channel 8 have their ends beveled as clearly illustrated in Fig. 1 to form a right angular frame for the panel 4. The top of the frame 5 includes two strips 12 and 13. The strip 90 12 has two filling pieces 14 and 15 secured thereto and are designed to extend transversely of the door and can, with the strip 12, be removed from the frame to permit the glass panel 4 to be slid downwardly from the top between the sides of the side channels 6 and between the sides of the bottom channel 8, it being noted that the strip 13 is brazed or otherwise secured to one of the sides of each of the side channels 6 and 7. 95

The filling strips 14 and 15 have threaded 100 holes 16 and 17, and screws 18 are designed to be inserted through the strip 13 to secure the filling pieces and strip 12 to the strip 13 so as to form a complete frame after the glass panel has been inserted.

To remove the glass panel 4, it is merely necessary to remove the screws 18 to permit the strip 12, and with it the filling pieces 14, to be taken off, then the glass panel can be 110 slid out of the frame in the same manner in which it was inserted.

Hinges 19 are provided to swing the door 3 on the casing 1, the rear surface of the casing being provided with metal facing plates 20 and 21. Bolts 22 secure the leaves 5 23 of the hinges 19 to the casing 1, the bolts having their ends 24 engaging the facing plate 20 so as to have a secure bearing between the metallic leaves 23 of the hinges and the plate 20.

- 10 The plate 21 is secured to the casing by bolts 22^a, and these bolts are preferably provided with heads to insure a secure binding action between the casing and said plate 21. The leaves 25 of the hinges are secured by 15 screws 26 to the side channel 7, the screws engaging threaded openings 27 in the filling strip 10. Thus a secure mounting is provided for the screws 26 and hinges 25 which is fully capable of supporting the door 3.
- 20 The plate 20 has an inturned rounded corner portion 28 which projects within the opening 2 and forms an abutment for the inner surface of the side channels 6 so as to prevent any splashing of the water within 25 the stall from working its way out between the door and the casing 1. The facing plate 21 also has an inturned corner portion 29 which projects within the opening 2 and forms an abutment for the side channels 6.
- 30 This corner portion 29 serves in the same capacity as the corner portion 28 and also has an opening 30 to receive a bolt 31 which is mounted within a case 32.

The case 32 is secured to the inner surface 35 of the side channel 6 and a spring 33 serves to move the bolt 31 into the opening 30 to hold the door in a closed position. The bolt 31 is beveled at its outer end so that the mere closing of the door permits the spring 40 to move the bolt into locking engagement with the plate 21.

The case 32 is provided with an extension 34 having a handle 35 thereon which projects into the interior of the stall and can 45 be grasped by an occupant of the stall to either open or close the door from the inside.

A handle 36 is secured to the outer surface of the side channel 6 by a screw 37, the screw having a threaded end which engages 50 a threaded opening 38 in the filling strip 9, thus the door can be conveniently opened or closed from the inside or from the outside.

The bottom of the opening 2 is on a slightly higher level than the upper surface 55 39 of the base 40 of the casing 1 so that water falling on the base surface 39 will not run out through the bottom of the opening 2 (see Fig. 2).

To further guard against the splash of the 60 water from running out of the stall through the bottom of the opening 2, I provide a splash guard 41. This splash guard is secured to the bottom channel 8 by means of screws 42 and forms a slanting shed which 65 deflects any water running down the inner

surface of the door to the surface 39 of the base 40.

In the form of my invention shown in Fig. 6, I have illustrated a modification in which one of the side channels is made up 70 of two sections 43 and 44. The section 43 is L-shape, while the section 44 is in the form of a flat strip. A filling strip 45 is soldered, brazed, or otherwise secured to the sections 43 and 44. In all other respects this 75 construction is similar to that described in connection with the side channels 6 and 7.

By the above described construction, an extremely durable frame is provided for the panel 4, and this frame can be quickly and 80 easily constructed. The frame and the adjacent portions of the casing 1 form a secure and durable mounting for the door 3, and the hinges can be made comparatively small and still adequately perform their functions. 85

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 90

Having thus described my invention, what 95 I claim as new and desire to secure by Letters Patent is:

1. A door including a frame in which the lower horizontal portion and upright joining portions are made of channels, each of 100 said portions having a filling strip extending in the direction of its length and spanning the distance between the inner surfaces of its sides, said filling strips being set in beyond the inner edges of said sides; and a panel having edge portions fitting in the space between said surfaces and between said inner edges and the adjacent surfaces of said filling strips, said frame also including a top portion having a detachable outer 105 side section, said section including a portion forming an abutment for the upper edge of said panel whereby when said detachable section is removed the panel can be slid upwardly out of said frame, substantially as 110 described.

2. A door including a frame made up of channels; a panel having edge portions fitting within said channels; and filling strips extending within said channels in the direction of the length thereof and spanning the distance between the inner surfaces of the sides of said channels whereby the filling strips form reinforcements for the sides of the channels and abutments for the edges 125 of said panel, the channel of the upper portion of said frame being made in two substantially horizontal sections, one of said sections having certain of said filling strips secured thereto and being detachable to 130

gether with said latter mentioned filling strips from the other section to permit the entire panel to be slid out of the frame, substantially as described.

- 5 3. A device of the character described having a supporting structure with an opening therein; a door for closing said opening and including a frame made up of channels; a panel having edge portions fitting within
10 said channels; filling strips extending within said channels in the direction of the length thereof and spanning the distance between the inner surfaces of the sides of said channels whereby the filling strips form
15 reinforcements for the sides of the channels and abutments for the edges of the panel,

said filling strips having threaded openings therein; and hinges secured to said frame and supporting structure, said hinges including securing screws which extend 20 through the side of one of said channels and fit within said threaded openings in the filling strip of the channel to which they are attached, substantially as described.

In testimony whereof I have signed my 25 name to this specification in the presence of two subscribing witnesses.
